2,067,827

YARN GUIDE AND FOLDER

Oswald Sheldon Carliss, Providence, R. I., assignor to H & B American Machine Company, a corporation of Maine

Application September 18, 1935, Serial No. 41,122

12 Claims. (Cl. 19—157)

This invention relates to long drafting textile apparatus, and has for one of its objects to provide a device therefor adapted for controlling the fibers of the sliver or roving between each successive drafting operation as the strand of fiber passes without interruption of its travel, in a single continuous process, from one set of drafting elements to the next succeeding set of draft rolls of the apparatus.

Another object of the invention is to provide a simple device capable of holding and carrying the sliver or roving without sagging or tearing apart in its travel, which is easily and economically manufactured and which embodies in its construction simple and efficient means to bring about a proper arrangement and distribution of the fibers relative to the central axis of the sliver.

Another object of the invention is to provide a simple device to act on the outwardly projecting or loose outer fibers of the sliver or roving in a positive manner to guide and turn them inwardly towards the middle or main body portion of the strand and to arrange them without compression in substantially parallel form lengthwise thereof to prevent the fibers at the outer edges of the sliver from fraying and thus avoid loss of these fibers as lint or waste.

Another object of the invention is to provide a device for holding, guiding, turning and folding the outer fibers at the edges of the strand longitudinally over itself in a series of simultaneous operations within the single unit to form the sliver to a shape which will hold the fibers of the strand together without tearing apart or spreading as it travels from one draft stage to the next succeeding one, yet without imparting a compression to the strand or by placing therein what is commonly termed in the art as a "false twist".

A further object of the invention is to provide a simple unitary device for folding the outer edges of the strand of sliver or roving inwardly towards its middle or central portion by means thereon which are relatively non-movable and non-rotatable.

With these and other objects in view as will be apparent from the following disclosure, the invention consists of certain novel features of construction, as will be more fully described and particularly pointed out in the appended claims.

In the accompanying drawing, in which like reference numerals indicate like parts:

Fig. 1 is a vertical sectional side elevation of a roving frame showing the device of the present

invention applied thereto and illustrating its relation to the draft rolls;

Fig. 2 is a fragmentary top plan view of a portion of the frame shown in Figure 1, illustrating the operation of the folder device on the strand 5 of sliver;

Fig. 3 is a rear view in perspective of a sliver folder device which is the subject of this invention;

Fig. 4 is a frontwise view in perspective of the 10 folder device shown in Figure 3;

Fig. 5 is a detail view in perspective of the main body portion of the folder device shown in Figure 3;

Fig. 6 is a detail view in perspective of the rear 15 element of the folder device shown in Figure 3, for completing the fold in the sliver;

Fig. 7 is a detail view in perspective of the scroll finger or horn of the folder device shown in Figure 3 for initially upturning the sliver to 20 start the fold therein; and

Fig. 8 is an enlarged cross-sectional view of the folded sliver taken along the line 8—8 of Figure 2.

In the usual production of yarn of cotton or 25 other fiber by many of the well known drafting systems in which the sliver or roving is acted upon successively by a series of drafting rolls to bring the strand to the desired size but without interruption in its travel, the chief problem 30 involved is how to attain a uniform control of the fibers, particularly those which project outwardly from the yarn and to prevent any localized flying apart of the fibers to the extent that they cannot be properly twisted together yet 35 at the same time permitting sufficient freedom to effect a proper distribution of the fibers in the yarn at the end of the drafting operation. Hence, the optimum condition is one in which there be distributed a major proportion of the 40 longer fibers at the axis of the yarn, with the shorter fibers towards the outside portions and uniformly distributed longitudinally thereof. Of the various methods heretofore practiced, one has involved the use of a pair of power driven 45 rolls engaging the strand of fibers for folding and condensing the strand between each successive drafting operation as it passes in a continuous process through the machine. One of these rolls is provided with a peripheral groove, while the other has a complementary peripheral rib or tongue which interfits within the groove in the other roll; the rolls being positively driven in such a manner that the contacting surfaces thereof travel with and move in the same direc- 50

55

tion and speed as the strand of fibers to fold and condense the strand as it issues from the drawing rolls.

Various other constructions have also been devised in the past in an attempt to overcome these difficulties, such as for example the use of traveling aprons, as are employed in several types of long draft spinning systems, in order to support and convey the yarn as it is drafted from 10 one nip roll to the next, but they all have yet remained not entirely satisfactory as meeting the rather stringent requirements in this line, owing to such objections as lack of simplicity in design, expensiveness of manufacture and maintenance in operation, and the inconveniences and difficulties attendant to interference with the natural movement of the fibers arising from continuous contact therewith and the resulting formation of lumps and bunches therein by retention of fly and other waste. In accordance with 20 this invention a device is provided which is devoid of relatively movable members and is particularly adapted for supporting, guiding, turning and folding relative to the main sliver body the 25 outer fibres of a strand of sliver or roving without compressing the same laterally or otherwise, in which the device is formed in three parts comprising a front finger or horn depending downwardly to engage and initially crease and turn 30 the edges of the strand to start the fold in the sliver, a body member for supporting the sliver and having a head portion shaped to turn up the outer fibers of the strand as it passes therethrough, and a rear member having a shaped 35 portion cooperating with the body member and the horn to complete the fold; and the following is a detailed description of the present embodiment of the invention, illustrating the preferred means by which these advantageous results may be accomplished:

With reference to the drawing, the invention is there illustrated in connection with a roving frame, in which the stationary part of the frame or roll stand is designated 10 having suitable bearing blocks in which the lower fluted rolls 11, 45 12, 13, 14, 15, 16 and 17, respectively, are mounted, while along the overarm 20 the upper rolls 21, 22, 23, 24, 25, 26 and 27 are mounted in suitable bearings and cooperate with the respective lower rolls in each of the pairs of rolls. The 50 upper roll 28, which is shown as resting on the fluted bottom roll 18, see Figure 1, is a smooth surfaced slip roll which is usually made of metal and has a selected weight, whereas the rest of the upper rolls are leather covered. The upper rolls may be weighted in any suitable manner as is the usual practice well known in the art and which forms no particular feature of the present invention. The rolls 12, 22 are rotated faster 55 than the rolls 11, 21 to provide a draft of the work. Rolls 13, 23, however, rotate at the same speed as the previous set of rolls 12, 22, so that in this stretch or zone of travel of the work no draft occurs. Similarly, draft occurs between 60 rolls 13, 23 and 14, 24, whereas no draft is incurred between the rolls 14, 24 and 15, 25, the 65 yarn being given the final draft between the rolls 15, 25; 16, 26 and 17, 27, respectively.

The sliver or roving folder guides 30 and 31, 70 which are the subject of this invention, are shown mounted on the bars 33 and 34, respectively, the bars being arranged for reciprocation axially with respect to the rolls by suitable mechanism (not shown). The sliver 35 passes over the carrier roller 36 and is led through the

draft rolls in succession, the preparatory draft being applied to it between the rear rolls 11 and 21 and the intermediate rolls 12 and 22, and then folded as it passes through the folder guide 30, followed by a second draft thereto by the intermediate rolls 13 and 23 and the next adjacent rolls 14 and 24, after which it is again folded during passage through the folder guide 31, and it is then subjected to a longer draft between the intermediate rolls 15 and 25, 16 and 26, and the 10 front rolls 17 and 27. As the sliver emerges from the front pair of rolls 17 and 27 it is wound upon a bobbin in the usual manner well known in the art during which it receives the amount of twist desired to afford it the required strength. 15

As illustrated in the drawing, each of the sliver folder guide members 30 and 31, respectively, consists of a thin elongated strip member, such as metal sheet stock or stamping, although other suitable non-metallic materials 20 may be used, having a body portion 40 which forms a vertical standard and is provided with an opening 41, adjacent to its lower end for securing the guide member to the reciprocable bars 33 and 34, respectively. The upper terminal end of the folder guide is provided with an indented guiding and turning portion which is shown in Fig. 5 of the drawing as being bifurcated to provide the fingers 42 and 43 between which is formed a U-shaped notch 44 30 which is given a slight flare at the entrance and exit sides thereof to provide a smooth rounding surface for the entrance of the sliver and for confining it so that any of the projecting ends of the fibers will when the strand is folded, be 35 lifted and partially turned up and back towards the middle of the strand as it passes therethrough. The fingers 42 and 43 are shown as being of unequal length, the longer finger 43 having formed integrally with its terminal end 40 portion a pair of oppositely extending arms 45 and 46, respectively, the inner ends of which, at their point of juncture, project outwardly from the side faces of the guide member in a direction at substantially right angles thereto. 45 The arm 45 is shown as being bent to form a frame or clamp member 47 having the vertical clamping portions 48, 49 and 50, respectively, for supporting a removable sliver guide member 51 adjustably mounted therein. The clamp 47 50 is spaced from the adjacent side face of the standard 40 with the clamping portion 49 being substantially parallel thereto. The guide member 51 is provided with an inverted indented guiding and turning portion which, as 55 illustrated in Fig. 6 of the drawing, comprises a U-shaped notch 52 formed through the wall at its bottom end, the entrance and exit side portions of which are slightly flared to provide a smooth rounding surface for movement of the sliver. This guide member 51 is adjustably secured and locked in the clamp 47 by means of a screw 53 mounted in the clamping portion 48, and the guide member 51 is held in the clamp 47 with its lower end portion overhanging 60 downwardly and extending along the upper end portion of the standard 40 but spaced therefrom, the opposed side faces of the guide member 51 and the upright standard 40 being substantially parallel and with the U-shaped 65 notches 52 and 44, respectively, being axially aligned with respect to each other, whereby the notch 52 may serve to turn in the outside edges 70 of the sliver into the center portion of the main sliver body and complete the folding process. 75

In order to direct the sliver to the notch 44 and preliminarily turn up the outer edges of the sliver and shape in advance of its entrance to the notch, a scroll-shaped horn or finger 55 is 5 mounted at the outer end of the outwardly extending arm 46 and depends downwardly therefrom with the tip of its outer end portion forming a curved finger disposed immediately in front of the entrance of the U-shaped notch 44 10 and axially aligned with respect thereto. The inner end of the horn 55 is adjustably mounted on the arm 46 by means of a bolt 56 and nut 57 passing through a suitable slot 58 formed in the arm 46 and disposed longitudinally thereof, whereby the horn may be adjusted to the proper position relative to the notch 44, as may be desired.

In practice, it is essential that the sliver contacting portions of the notches 44 and 52, and 20 the horn 55 be composed of a material capable of developing considerable smoothness, such as for example brass, steel or other suitable metal, porcelain, hard enamel or molded resinoid substances, which may be applied thereto as a coating or the whole member itself may be formed 25 entirely of the material selected.

The operation of the device is obvious from the above disclosure. The sliver or roving as it emerges from the draft rolls passes under the 30 horn 55 to thereby partially turn up the edge portions of the strand and direct it to the notch 44 of the support as it moved therewith, the sides 42 and 43 of the notch serving to act on the sliver as it enters the notch to finish turning up the upturned edges to conform to the shape of the notch. Upon passing through the 35 notch 44 the upturned edges of the sliver are then turned in and folded transversely of its body without lateral compression thereof by contact with the sides of the notch 52 in the 40 rear guide member 51.

As shown in Figure 8 the folded sliver as it leaves the device is in an uncompressed condition with the fibers adjacent to the outer 45 edges being turned in and arranged uniformly about the sliver core.

In accordance with this construction, the open side 42 of the guide renders it easy to thread the sliver in the notch 44. By making the device of a stamping, the small surface of contact provided thereby eliminates drag and bunching of the sliver as it moves therethrough. Furthermore, the absence of moving parts enables all the fibers of the sliver to pass through 50 the device without any speed differential being imposed thereon.

By this device, therefore, a very simple arrangement of long drafting may be accomplished in which the folder guide is of simple 60 construction which utilizes a small number of parts and may be manufactured economically and easily assembled in position on the drafting apparatus.

The foregoing description is directed solely 65 towards the construction illustrated, but it is to be understood that the privilege is reserved of resorting to all the mechanical changes to which the device is susceptible, the invention being defined and limited only by the terms of 70 the appended claims.

Having thus described the invention, what is 75 claimed as new and desired to secure by Letters Patent is:

1. A device for use in long draft textile ma- 75 chines for controlling and folding textile sliver,

roving and the like preparatory for drafting of the same comprising a support, means on said support to receive and longitudinally distribute the edges of the sliver in an uncompressed condition during its passage therethrough, and creasing means in the line of travel of and adjacent to and cooperating with said sliver distributing means on said support for directing the sliver thereto and initially forming a longitudinal fold in it directly in advance of its 10 travel therethrough.

2. A device for use in long draft textile machines for controlling and folding textile sliver, roving and the like preparatory for drafting of the same comprising a support, means on said support for supporting and turning up the edges of the sliver and longitudinally distributing them in an uncompressed condition during passage of the sliver therethrough, and creasing means depending immediately in front of said sliver 20 turning means on said support and cooperating therewith for directing the sliver thereto and initially forming the fold in it in advance of its travel therethrough.

3. A device for use in long draft textile machines for controlling and folding textile sliver, roving and the like preparatory for drafting of the same comprising a support, means on said support for supporting and turning up the edges of the sliver in an uncompressed condition during 30 its passage therethrough, creasing means depending in front of and adjacent to and cooperating with said sliver turning means on said support for directing the sliver thereto and initially forming the fold in it directly in advance 35 of its travel therethrough, and means disposed adjacent to the exit portion of said sliver turning means on said support for guiding and turning in the edges of the sliver transversely thereof and completing the fold therein.

4. A device for use in long draft textile machines for controlling and folding textile sliver, roving and the like preparatory for drafting of the same comprising a support, nonrotatable means on said support for supporting and turning up the edges of the sliver and longitudinally distributing them in an uncompressed condition during its passage therethrough, non-rotatable 45 creasing means depending adjacent to and cooperating with said sliver turning means on said support for directing the sliver thereto and initially forming the fold in it directly in advance 50 of its travel therethrough.

5. A device for use in long draft textile machines for controlling and folding textile sliver, 55 roving and the like preparatory for drafting of the same comprising a fixed support, creasing means associated with said support for preliminarily forming a longitudinal fold in the sliver, means on said support for supporting and turning up the edges of the sliver and longitudinally distributing them in an uncompressed condition during its passage therethrough, and means spaced from said support and depending therefrom adjacent to the exit portion of said sliver 60 turning means thereon for guiding and turning in the edges of the sliver transversely thereof and completing the fold therein.

6. A device for use in long draft textile machines for controlling and folding textile sliver, 70 roving and the like preparatory for drafting of the same comprising a fixed support, means associated with said support for preliminarily starting the fold in the sliver, means on said support for supporting and turning up the fibers 75

of the sliver which are in close proximity to the outer edges thereof yet without compressing the same, and means adjacent to the exit portion of said sliver turning means for receiving 5 and folding the upturned fibers inwardly adjacent to the central body of the sliver and arranging them longitudinally therewith.

7. A device for use in long draft textile machines for guiding and longitudinally folding 10 sliver, roving and the like preparatory for drafting comprising a support, means on said support for guiding and turning up the edges of the sliver, adjustable means depending downwardly from a point immediately in front of the entrance 15 of the guiding and turning means in said support and extending lengthwise of the sliver whereby the fold in the sliver is preliminarily formed directly in front thereof, and means depending downwardly from a point adjacent to 20 the rear portion of said fiber-turning means in said support and in axial alignment therewith whereby the edge portions of the fold in the sliver are turned inwardly across and towards the center body of the main sliver portion yet 25 without it being compressed to a materially greater density than it had prior to folding.

8. A device for use in long draft textile machines for guiding and longitudinally folding sliver, roving and the like preparatory for drafting 30 comprising a support, means on said support for guiding and turning up the edges of the sliver, adjustable means depending downwardly from a point immediately in front of the entrance of the guiding and turning means in said support whereby the fold in the sliver is initially 35 formed directly in front thereof, and adjustable means depending downwardly from a point adjacent to the rear portion of said fiber-turning means in said support and spaced therefrom 40 whereby the fold in the sliver is turned inwardly across and toward the center body of the main sliver portion yet without it being compressed to a materially greater density than it had prior to folding.

45 9. A device for use in long draft textile machines for guiding and folding sliver, roving and the like preparatory for drafting comprising a support, means including a notch on said support for guiding and controlling the fibers, a horn depending downwardly from a point immediately in front of the entrance of the guiding means in said support whereby the fold in the sliver is formed directly in front thereof, and means including a notch adjacent to the rear 50 portion of said fiber-controlling means in said support and spaced therefrom to receive the sliver whereby the fold in the sliver is turned inwardly toward the center of the main sliver portion yet without it being compressed to a materially greater density than it had prior to folding.

60 10. A device for use in long draft textile ma-

chines for guiding and folding sliver, roving and the like preparatory for drafting comprising a vertical standard provided with a U-shaped opening through the wall at its top end, a pair of transverse arms of unequal lengths extending outwardly in opposite directions from the side faces of said standard and joined at their inner ends to an upright arm portion of the U-shaped opening, the outer end of the shorter arm being bent at right angles thereto and parallel with the adjacent side face of the standard and spaced therefrom forming a clamp having a vertical clamping portion, a movable member vertically adjustable upon said vertical clamping portion and provided with an inverted U-shaped opening in its lower end, said movable member extending along a portion of the adjacent surface of the standard but spaced therefrom, adjustable means for removably securing the vertically movable member in the clamp, and a scroll-shaped horn adjustably mounted at the outer end of the longer projecting arm, said horn having a depending end portion forming a finger disposed in advance of but immediately in front of the U-shaped sliver-receiving opening at the top of the standard and in axial alignment therewith for folding the sliver and retaining it in that form during its passage through the device.

11. A device adapted for use in long draft 30 textile machines for guiding and longitudinally folding textile sliver, roving and the like preparatory for drafting of the same comprising a support having an indented guiding and turning surface for turning up the edges of the sliver and disposed adjacent to the upper end of the support, means projecting downwardly in the line of travel of said sliver to initially crease the same prior to its reception by said indented sliver turning means in said support, and means 40 including an inverted indented guiding and turning surface for turning in the upturned edges of the sliver laterally in a direction across the sliver to complete the fold.

12. A device adapted for use in long draft 45 textile machines for guiding and longitudinally folding textile sliver, roving and the like preparatory for drafting of the same comprising a support having an indented guiding and turning surface for turning up the edges of the sliver and disposed adjacent to the upper end of the support, means on said support projecting downwardly therefrom in the line of travel of said sliver to initially crease the same prior to its reception by said indented sliver turning 50 means in said support, and adjustable means including an inverted indented guiding and turning surface for turning in the upturned edges of the sliver laterally in a direction across the sliver to complete the fold.

60 OSWALD SHELDON CARLISS.
